Primary Examiner — Cathron C Brooks

Assistant Examiner — Christian P. McLean

(74) Attorney, Agent, or Firm — Cook Alex Ltd.

(57) **CLAIM**

The ornamental design for a bottle, as shown and described.

DESCRIPTION

FIG. 1 is a perspective view from the bottom of a bottle showing the new design;

FIG. 2 is a perspective view from the top of the bottle of FIG. 1;

FIG. 3 is a side elevational view of the bottle of FIG. 1;

FIG. 4 is a top plan view of the bottle of FIG. 1; and,

FIG. 5 is a bottom plan view of the bottle of FIG. 1.

The dot-dash broken line illustrates the boundary of the design and forms no part of the claim. The remaining evenly dashed broken lines illustrate portions of the bottle that form no part of the claimed design.

1 Claim, 4 Drawing Sheets(56)
